SPRAY BOOTH

Eric Gustafsson, Chicago, Ill., assignor to Binks
Manufacturing Company, Chicago, Ill., a cor-
poration of Delaware

Application December 1, 1937, Serial No. 177,563

13 Claims.

(Cl. 91—60)

5 My invention relates to spray booths within which objects are coated by spraying them with liquid (or at least generally liquid) coating materials, and more particularly to the economical and effective reclaiming of coating material particles from the portion of the spray and spray fumes projected past or deflected from the object toward which the spray is directed.

10 In spray booths of this class it has long been customary to provide the object-housing part of the booth with an upright back or apron against which the fumes of the said further projected or deflected portion of the sprayed material will impact, and have a film or sheet 15 of liquid flow downwardly along the forward face of the said booth back for absorbing the coating material particles of the fumes which reach the said booth back. It has likewise already been customary to guide such fumes out of the 20 spray booth proper to a more rearward fume-washing chamber, the lower part of which forms a settling tank for receiving material washed off the said booth back, and to provide means above this tank for removing material particles from 25 the fumes which pass above the settling tank and which are then drawn upwards toward a flue.

30 The last named means have usually included sprays, either of fresh water or of liquid drawn from the settling tank, and spaced eliminator plates disposed at higher elevation than the said sprays, so that material-laden liquid reaching these plates will flow downward along the said plates and drip down into the settling tank.

35 However, the arrangements heretofore proposed for the just recited purposes have had the following shortcomings, the overcoming of which constitutes the main objects of my present invention:

40 (1) When the liquid used for flushing coating material particles off the surface of the spray booth back or apron issues from ports in a pipe, ports of quite small diameter are ample for affording the needed downwardly flowing film, 45 and the use of such small-diametered ports is highly desirable because of the cost of pumping an excessive quantity of the apron-flushing liquid. However, such otherwise suitable small-diametered ports easily become clogged, thereby 50 making the resulting film of liquid streaky and inadequate unless the ported pipe is frequently flushed out and the ports cleaned.

55 (2) The spray provisions commonly employed in the wash compartment of a spray booth usually allow an undesirable percentage of the fume

material to be drawn up into the flue and wasted.

(3) Although the eliminator plates are usually at considerably higher elevation than the pipe from which the flushing liquid issues, the drip from these plates must first drop into the settling tank in the lower part of the fume-wash compartment, and thereafter must be forcibly pumped up to the said pipe unless fresh water is used for such flushing. Consequently, a corresponding and considerable expense is involved for the said pumping.

10 Illustrative of the manner in which I overcome the above recited objections and also attain other desirable advantages over the provisions heretofore proposed for similar purposes,

15 Fig. 1 is a front elevational view of a spray booth embodying the invention, with parts broken away to show interior construction;

20 Fig. 2 is a transverse sectional view in a vertical plane represented by line 2—2 in Fig. 1 of the drawings, with certain parts shown in side elevation;

25 Figs. 3 and 3a are fragmentary vertical transverse sectional views on an enlarged scale of alternative forms of the trough and apron features of the invention;

30 Fig. 4 is a fragmentary detail sectional view of the eliminator plates, taken in a plane represented by line 4—4 in Fig. 2 of the drawings;

35 Figs. 5, 6, 7, 8, 9 and 10 are fragmentary vertical sectional views showing alternative forms and arrangements of parts, corresponding more or less to Fig. 2; and

40 Fig. 11 is a fragmentary top plan view of the spray breaking feature of the invention.

45 Referring more in detail to the drawings the embodiment chosen to illustrate the invention is shown as a sheet metal structure comprising a booth or chamber 1 having a front opening 2, and a back wall 3. At the rear lower portion of the structure is a liquid tank 4, an end portion 5 (Fig. 1) of which extends out from the side of the structure, and is connected by way of a valved intake 6 to a liquid circulating pump 7 having an outlet or discharge pipe 8.

50 Intermediate of the front 2 and the back wall 3 of the structure is a transverse wall 9 in the form of an apron and constituting the back wall for the booth or spraying space. This apron has a rearwardly and downwardly curved lower end portion 10 and an upwardly and rearwardly curved upper end portion 11 with an upwardly extending flange 12. From the top 13 of the booth, rearwardly and downwardly extends a wall portion or distributing plate 14 having its 55

lower edge suitably spaced from the curved wall portion 11 to provide therebetween a slot or slit 15 through which liquid, such as water, flows downwardly in the form of a sheet or curtain 16 over the front surface of the apron 9 to flush such surface with the liquid, as water, to prevent the adhering and accumulation of spray material to and on the front face of the apron. The space above and between the wall portions 11 and 14 constitutes a trough 17 for receiving the liquid for flushing the forward or front face of the apron.

In the form shown in Figs. 2 and 3, the apron 9 is substantially inclined rearwardly, and the slit 15 is quite narrow. As shown in Fig. 3a the apron 9a may be vertical or but slightly inclined rearwardly, and the slot 15a may be wider, as desired, the trough 17a otherwise having the parts 14a, 11a and 12a corresponding to the same numbered parts in Figs. 2 and 3.

With a normal supply of liquid in the trough 17a, the slit 15a is of such a width as to permit the down flow of the liquid through the slit 15a and over the front surface of the apron as fast as the liquid is received in the trough. In the case of using a narrower slit, as slit 15, the liquid may accumulate in the trough 17, more or less, but preferably the slit is of such a width that the liquid distributed to the trough will flow down the wall portion 14 or 14a through the slit and onto the apron to flow down the forward face of the apron in the form of a sheet or curtain.

Between the lower end portion 10 and the open top of the tank 4 is provided an air passage 18, the air flow being from the opening 2, through the booth 1 and through the passage 18, as shown by the arrows.

The space between the rear wall 3 and the apron 9 constitutes an uptake passage 19 for the cleaning of the air from suspended particles, fume and other material which, it is desired, should not reach the atmosphere and be wasted. The upper end of the passage 19 communicates with an eliminator chamber 20 in which is located an eliminator 21. This eliminator (as shown in Figs. 1 and 2) extends across the width and along the length of the chamber 20, and is inclined or tilted downwardly from the rear wall 3 to the forward wall 3a of the chamber so that its forward end portion 22 is at a lower level or elevation than its rear end portion 22a. The chamber 20 is of greater depth than the uptake passage 19 to provide space forwardly for the lower end portion 22 of the eliminator whereby this end portion will be located over and above the trough 17 whereby the liquid flowing from the eliminator will flow or drop down into the trough 17, and not into and through the passage 19 and into the tank 4.

The eliminator, however, may be oppositely tilted, as shown in Fig. 10, that is, tilted downwardly from the forward wall 3a to the rear wall 3 of the chamber 20 so that the forward end portion 22 is at a higher level or elevation than its rear end portion 22a. In this case liquid running along the elements of the eliminator will drip from lower end portion down into the uptake 19.

The eliminator comprises a series of spaced corrugated plates 23 having zigzag portions 24 to provide therebetween tortuous air passages 25 for the upwardly flowing stream of liquid bearing air through the eliminator chamber 20 whereby the liquid or moisture carried by the air will adhere to the walls of the plates 23 and run or trickle down over the surfaces of these plates to the lower edges thereof. By reason of tilting

the eliminator the trickling down of the water will have a component movement or progression forwardly in the forms shown in Figs. 2, 5, 6, 8 and 9, or rearwardly in the form of Fig. 10, so that as the liquid descends it will have progress toward the lower end of the eliminator and drop from the lower end portions of the plates into the trough 17, or into the uptake passage 19 (Fig. 10).

The lower edges of these plates are so bent or curved as to form channels or troughs 26 in which the water running or trickling down the surfaces of the plates 23 accumulate or collect and along which the water flows to the lower end of the eliminator by reason of the latter being inclined or tilted. The rear and forward ends of the eliminator are respectively supported upon brackets 27 and 28 (in the form of angle bars) respectively secured to the inside of the back and front walls of the eliminator chamber 20.

The upper end of the chamber 20 communicates with an exhaust or discharge duct 29 leading to the atmosphere, this duct 29 having therein an exhaust fan 30 driven by a suitable power source, such as a motor 31.

Within the uptake chamber 19 and extending transversely thereof are manifold pipes 32 and 33 to the sides of which are connected sprayers 34 and 35 for projecting divergent water sprays 36 and 37 for washing the uprising stream of air in the uptake chamber 19. The pipes 32 and 33 at an end thereof extend out through a side wall of the structure and are connected to pipes 38 and 39 in turn connected to a pipe 40 communicating with the pump outlet pipe 8. The other ends of the pipes 32 and 33 are suitably plugged, as by plugs 32a and 33a.

While in Figs. 1 and 2 the sprayers 34 and 35 are shown as projecting the sprays 36 and 37 downwardly, they may be turned so as to project the sprays 36a and 37a upwardly as shown in Fig. 8, or with the sprayers 34 projecting the sprays 36a upwardly, and the sprayers 35 projecting the sprays 37 downwardly as shown in Fig. 5, or in any other way as desired.

Connected to and arising from the pipe 32 (see Figs. 1, 2 and 10) are pipes 41 having at their upper ends impact type nozzles 42 for projecting water or other liquid against overhanging buttons 43 to effect horizontal or substantially horizontal sprays 44 in the form of circular sheets. These sprays are at a level higher than the trough 17 or 17a so that some of the liquid will be projected or cast into the trough, or against the wall part 14, or a breaker (later described) to flow down into the trough 17 or 17a, and to so direct the spray projected toward the wall part 14 or 14a as to obtain a substantially even or uniform distribution of the liquid along the length of such wall part 14 or 14a whereby a uniform continuous sheet 16 of liquid will flow over the apron. The spray sheets 44 are of such extent as to cover the whole cross-sectional area of the uptake whereby the uprising air therein will be thoroughly washed before reaching the eliminator.

Because of the sprays 44 being in the form of circular sheets whereby the liquid is projected in all radial directions in the plane of the sheet produced at each nozzle, much of the spray sheet is projected at various angles, as along the lines 52 shown in Fig. 11, and is so deflected from the wall portion 14 or 14a, or the wall 3a, as to fall into the space in the chamber 20 above the uptake passage 19, and is lost so far as its use for supplying liquid for the apron is concerned. To avoid this condition it is preferable

to provide a breaker 51 (see Fig. 11) in the path of the forwardly projecting portion of the spray 44 to prevent deflection or splashing and to cause the liquid to trickle or flow down into the trough 17 or 17a, as upon the wall part 14 or 14a. The breaker 51 is preferably located above, as upon, the wall portion 14 or 14a and is preferably in the form of a roll or coil of metal fabric, such as a coarse mesh screen, shown in end view in Figs. 2, 6, 7 and 10. This breaker extends over the whole length of the wall 14 or 14a, for the full width of the chamber 20. It is held in place by suitable retaining elements, such as U-shaped straps 53 passing around the breaker, as near the ends thereof, and having their ends 54 secured in any suitable way to the wall portion 14 or 14a, as shown in Figs. 2, 6, 7 and 10. As the forward portions of the sprays 44 impacts the breaker 51, the jets are baffled and broken up to be further distributed, and the liquid trickles or flows down the open work of the breaker to the wall 14 or 14a of the trough 17 or 17a.

Locating the breaker on the wall portion 14 or 14a is also advantageous in that it is below the lower end portion of the eliminator (as shown in Figs. 1, 2, 5, 6, 8 and 9) and hence will receive the drippings 49 to also baffle further distribute and break them up instead of their being splashed from the wall part 14 or 14a and into the chamber space above the uptake passage 19.

In lieu of the spray means 41-42-43 shown in Fig. 2, spray means of the type shown in Fig. 7 may be used, and wherein are shown pipes 41a, suitably connected to the pipe 32, having at their upper ends spray heads 42a having a slit 43a in the forward side thereof for projecting or casting a substantially flat spray 44a in the form of semi-circular sheets. Since the spray heads 42a are located at the rear near the rear wall 3, the liquid is projected with necessarily greater force than required in the case of projected liquid in the type of sprayers shown in Fig. 2. In order to baffle and break up these sprays, the breaker 51 is preferably provided on the wall part 14 with the same advantages as previously mentioned.

In some cases the liquid for flushing the apron is supplied from the upwardly projecting sprays 36a as shown in Figs. 5, 6, 8 and 9. These sprays are preferably projected to a sufficient height to impact the eliminator, and to drop from the eliminator, the forward portions of the sprays hitting the forward portions of the eliminators, and dripping into the trough 17 or 17a. In such case the eliminator acts as a breaker means to baffle, further distribute and break up the spray portions mentioned. Some of the forward portions of the sprays may not reach the eliminator but will fall or drop back into the trough 17 or 17a, as upon the plate or wall part 14 or 14a, as clearly shown in the drawings. The use of the breaker 51 will not be necessary but may be used if desired. It is not necessary where the spray hits the eliminator because the eliminator plates 24 will act to break up the spray and cause the liquid to drip upon the wall part 14 or 14a of the trough 17 or 17a, the eliminator in such cases acting also as a breaker.

In Fig. 6, in addition to showing the upward spraying against the eliminator, there is shown also pipes 41b connected to a pipe 55 extending horizontally across the uptake passage 19 and parallel to the pipes 32 and 33, and connected to the fitting 56 connecting the pipes 38, 39 and 40 together. At the upper ends of the pipes 41b are spray heads 42a having spray slots 43a for for-

wardly casting or projecting substantially flat sprays 44b in the form of semi-circular sheets. These spray heads are located near the trough 17 or 17a and preferably project the sprays against the breaker 51 as shown and for the same purposes are stated above. Where an abundant supply of liquid is needed for flushing the apron, the use of these sprays in addition to the upwardly projecting sprays 36a is advantageous, especially when the eliminator is located somewhat high above the trough.

In some cases it is preferable to have the eliminator located as low as possible with respect to the trough. In Fig. 9 is shown such a structure, wherein the lower forward end portion 22 of the eliminator is immediately above the trough 17 or 17a. The upward spray 36a impinges the plates 24 of the eliminator, is broken up thereby, and liquid trickles along the plates, and drips down in the trough 17 or 17a, as upon the wall 14 or 14a as shown. More of the spray 36a is then available for supplying the flush liquid for the apron than in the case where the eliminator is located higher, as for example as shown in Figs. 5, 6 and 8.

In use the operator stands at the opening 2 with the spray gun 45 in his hand to project a spray 46 against the article to be coated. The article is suitably located or supported in what may be termed the spraying zone 47. The air flows in through the opening 2 past the operator and the work to the passage 18 and thence upward in the uptake chamber 19 to the eliminator 21 and exhaust duct 29. The fumes given off from the spray will be drawn by the air and be washed out of the air as it passes through the water sprays.

Some of the spray from the gun will be projected past or deflected from the work toward the apron 9 into the liquid curtain or sheet 16 which carry the particles down into the tank 4 to settle therein and thus be reclaimed. As the water flows down over the front surface of the apron it will be drawn by adhesion rearwardly along the curved portion 10, at the lower end of the apron, and will drop therefrom in the form of a spray 48 so that it will effect a preliminary cleaning of the air in the passage 18.

It will be noted that the liquid for the curtain flows in a circuit from the trough 17 through the slot 15 over the surface of the apron 9, in the tank 4, by way of the pump 1, and sprayers 42-43, a part of the spray of which being projected into the trough 17.

The uprising air in the uptake chamber is washed by the liquid sprays 36 and 37, or 36a and 37a, and also by the liquid sprays 44, or 44a to clean it of all fume and the like. The air then passes upwardly through the tortuous passages 25 between the plates 23 of the eliminator 21 whereby the liquid or moisture carried by the air will adhere to the walls of the plates 23 and run or trickle down the surfaces thereof and accumulate or collect in the inclined troughs or channels 26 to flow downwardly therealong and be discharged at the lower ends thereof and onto the wall part 14 or 14a of the trough 17 or 17a (or drop into passage 19 in the form shown in Fig. 10) for the purpose of assisting in supplying the water for the water curtain. The liquid spray portion (44) projected over the trough 17 or 17a and against the breaker 51, will be broken up and caused to trickle or flow down the breaker onto the wall part 14 or 14a of the trough 17 or 17a.

To the pipe 8 is connected a valved pipe 50 from a source of liquid (not shown) for furnishing fresh liquid as may be desired or required.

While I have herein described and upon the drawings shown an illustrative embodiment of the invention it is to be understood that the invention is not limited thereto but comprehends other constructions, arrangements of parts, details, features and the like without departing from the spirit of the invention.

Having thus disclosed the invention,

I claim:

1. In a spray booth having a spraying chamber, an air washing chamber communicating with the lower rear portion of said spraying chamber, a back wall for the spraying chamber and having as part thereof a generally upright apron toward which waste spray material is directed, and a liquid receiving tank in the lower part of the washing chamber and beneath the lower end portion of said apron, a liquid supplying device for flushing said apron comprising a liquid distributing plate disposed in the upper portion of said washing chamber at a higher elevation than said apron and in spaced relation to the upper portion of said apron to provide an opening for discharging liquid therethrough and, over the upper portion of the forward face of said apron, a liquid spraying device disposed in said air washing chamber for washing the air passing therethrough, and a liquid projecting device located in an upper portion of said washing chamber about level with said plate to project liquid toward and against said plate to supply liquid for flushing the front face of said apron.

2. In a spray booth having a spray chamber provided with a back wall having as a part thereof of a generally upright apron toward which waste spray material is directed, and an upwardly extending air washing chamber behind the apron, a device for supplying liquid for flushing the forward face of the apron, comprising a trough-like structure having a wall part disposed in the upper portion of said washing chamber and in spaced relation to the upper end portion of the apron to provide an opening for the flow of liquid therethrough and over said front face of the apron, a liquid spraying device disposed in said air washing chamber for washing the air passing therethrough, and a liquid projecting device disposed in an upper portion of the washing chamber and located rearwardly of and at a higher level than said trough-like structure for projecting liquid toward said wall part to supply flushing liquid thereto.

3. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow

downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron.

4. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron.

5. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron.

6. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron, and an eliminator so located in the upper portion of said washing chamber and above said last mentioned liquid projecting means as to drop liquid upon said inclined plate for supplying liquid for flushing said exposed surface of said apron.
7. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron, and an inclined eliminator located in the upper portion of said washing chamber and above said last mentioned liquid projecting means with the lower end of said eliminator disposed over said inclined plate for dropping of liquid therefrom upon said inclined plate for supplying liquid for flushing said exposed surface of said apron.
8. In a spray booth having spraying and washing chambers with a generally upright apron separating said chambers and with openings provided between said chambers at the upper and lower ends of said apron whereby air may flow from said spraying chamber to said washing chamber through the lower of said openings and flushing liquid may flow through the upper of said openings to and over the surface of said apron which is exposed to said spraying chamber and toward which spray fumes are directed, and wash fluid projecting means in said washing chamber for washing out the spray fumes carried by the air passing through said washing chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing chamber at about the level of the upper end of said apron for projecting liquid toward and against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron, and an eliminator so located in the upper portion of said washing chamber and above said last mentioned liquid projecting means as to drop liquid upon

said inclined plate for supplying liquid for flushing said exposed surface of said apron, said eliminator having at its lower part collecting channels for receiving liquid trickling down in said 5 eliminator, said channels being inclined with the lower end portions thereof located above and over said inclined plate for liquid flowing along said channels to drop upon said inclined plate.

10. In a spray booth having spraying and washing chambers with a generally upright apron separating said chambers and with openings provided between said chambers at the upper and lower ends of said apron whereby air may flow from said spraying chamber to said washing 10 chamber through the lower of said openings and flushing liquid may flow through the upper of said openings to and over the surface of said apron which is exposed to said spraying chamber and toward which spray fumes are directed, and 15 wash fluid projecting means in said washing chamber for washing out the spray fumes carried by the air passing through said washing chamber, a device for supplying liquid for flushing said exposed surface of said apron, comprising 20 a liquid distributing means above the upper of said openings for delivering a sheet of liquid across said opening to said apron to flow downwardly in the form of a sheet over said exposed surface of said apron, and liquid projecting 25 means located in the upper portion of said washing chamber at about the level of the upper end of said apron for projecting liquid toward and against a portion of said distributing means for supplying the flushing liquid delivered to 30 said apron, said distributing means comprising an inclined plate the lower edge of which is spaced from the surface of said upper end portion of said apron for providing an elongated opening parallel to said apron and across and 35 through which said sheet of liquid flows to flush the exposed surface of said apron, said liquid projecting means being provided with a narrow orifice for projection therethrough of liquid in the form of a horizontal sheet with a portion 40 of said sheet being projected toward and against said inclined plate for distribution of said liquid over said inclined plate.

11. In a spray booth having spraying and washing chambers with a generally upright apron 50 separating said chambers and with openings provided between said chambers at the upper and lower ends of said apron whereby air may flow from said spraying chamber to said washing chamber through the lower of said openings and flushing liquid may flow through the upper of 55 said openings to and over the surface of said apron which is exposed to said spraying chamber and toward which spray fumes are directed, and wash fluid projecting means in said washing 60 chamber for washing out the spray fumes carried by the air passing through said washing chamber, a device for supplying liquid for flushing said exposed surface of said apron, comprising a liquid distributing means above the upper 65 of said openings for delivering a sheet of liquid across said opening to said apron to flow downwardly in the form of a sheet over said exposed surface of said apron, and liquid projecting means located in the upper portion of said washing 70 chamber at about the level of the upper end of said apron for projecting liquid toward and against a portion of said distributing means for supplying the flushing liquid delivered to said apron, said distributing means comprising an 75 inclined plate the lower edge of which is spaced

from the surface of said upper end portion of said apron for providing an elongated opening parallel to said apron and across and through which said sheet of liquid flows to flush the exposed surface of said apron, a breaker on said 5 inclined plate for scattering the liquid projected thereagainst from said liquid projecting means to distribute the liquid over said inclined plate.

12. In a spray booth having spraying and washing chambers with a generally upright apron 10 separating said chambers and with openings provided between said chambers at the upper and lower ends of said apron whereby air may flow from said spraying chamber to said washing chamber through the lower of said openings and 15 flushing liquid may flow through the upper of said openings to and over the surface of said apron which is exposed to said spraying chamber and toward which spray fumes are directed, and wash fluid projecting means in said washing 20 chamber for washing out the spray fumes carried by the air passing through said washing chamber, a device for supplying liquid for flushing said exposed surface of said apron, comprising a liquid distributing means above the 25 upper of said openings for delivering a sheet of liquid across said opening to said apron to flow downwardly in the form of a sheet over said exposed surface of said apron, and liquid projecting means located in the upper portion of said 30 washing chamber at about the level of the upper end of said apron for projecting liquid toward and against a portion of said distributing means for supplying the flushing liquid delivered to 35 said apron, said distributing means comprising an inclined plate the lower edge of which is spaced from the surface of said upper end portion of said apron for providing an elongated opening parallel to said apron and across and through which said sheet of liquid flows to flush the exposed surface of said apron, a breaker on said 40 inclined plate for scattering the liquid projected thereagainst from said liquid projecting means to distribute the liquid over said inclined plate, said liquid projecting means being provided with a narrow orifice for projection therethrough and therefrom of liquid in the form of a horizontal 45 sheet with a portion of said sheet being projected toward and against said breaker to distributively scatter said liquid over said inclined 50 plate.

13. In a spray booth having spraying and washing chambers with a generally upright apron 55 separating said chambers and with openings provided between said chambers at the upper and lower ends of said apron whereby air may flow from said spraying chamber to said washing chamber through the lower of said openings and flushing liquid may flow through the upper of 60 said openings to and over the surface of said apron which is exposed to said spraying chamber and toward which spray fumes are directed, and wash fluid projecting means in said washing chamber for washing out the spray fumes carried by the air passing through said washing 65 chamber, a device for supplying liquid for flushing said exposed surface of said apron, comprising a liquid distributing means above the upper of said openings for delivering a sheet of liquid across said opening to said apron to flow downwardly in the form of a sheet over said exposed surface of said apron, and liquid projecting means located in the upper portion of said washing 70 chamber at about the level of the upper end of said apron for projecting liquid toward and 75

against a portion of said distributing means for supplying the flushing liquid delivered to said apron, said distributing means comprising an inclined plate the lower edge of which is spaced from the surface of said upper end portion of said apron for providing an elongated opening parallel to said apron and across and through which said sheet of liquid flows to flush the exposed surface of said apron, said distributing means also including an eliminator comprising a

plurality of generally upright and horizontally spaced corrugated plates to provide upward tortuous air passages therebetween, the lower edges of said plates being provided with collecting channels which slope downwardly toward a locus above and over said inclined plate for liquid flowing in said channels to drop upon said inclined plate.
